(57) **CLAIM**

The ornamental design for a lamp for manicure, as shown and described.

DESCRIPTION

FIG. 1 is a front, top and right-side perspective view of a lamp for manicure showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof; and,

FIG. 9 is an enlarged view, of circled portion 9, of FIG. 1, thereof.

The broken lines throughout the drawing figures depict portions of the lamp for manicure that form no part of the claimed design.

The dot-dash broken lines depict the boundaries of the FIG. 9 enlargement that forms no part of the claimed design.
